UNITED STATES PATENT OFFICE

2,675,221

GOVERNOR WITH HYDRAULIC FOLLOW-UP

Joseph S. Dale, Rockford, Ill., assignor to Dale Hydraulic Controls, Inc., Rockford, Ill., a corporation of Illinois

Original application March 18, 1946, Serial No. 655,086, now Patent No. 2,571,842, dated October 16, 1951. Divided and this application July 5, 1951, Serial No. 235,310

13 Claims. (Cl. 264—7)

1 This invention relates to engine-governor mechanism; in particular, it concerns novel apparatus for adjusting the speed control of such a governor as a function of the load on the prime mover being controlled thereby.

This application is a division of my copending application, Serial No. 655,086, filed March 18, 1946, and now Patent No. 2,571,842.

When the fuel supply to an engine is being regulated by a governor, it is often desirable, in the interest of stability, to cause the engine to slow down slightly as the load on it is increased. A slight downward speed adjustment as a function of engine load is particularly desirable in applications where several engines are being operated in parallel, to achieve equal division of the load among the various engines. The effect under consideration is known in the art as "speed droop."

The present invention concerns a particularly effective, simple, and mechanically stable apparatus for achieving speed droop. While I have herein shown my invention as applied to a particular type of hydraulic governor, my invention is not so limited and may, by obvious modifications, be employed with any of the familiar types of governors using fly weights and a speeder spring.

A specific object of my invention is to provide speed-droop mechanism characterized by unusual mechanical stability, particularly well adapted for holding its setting throughout long periods of operation.

Another object of my invention is to provide novel speed-droop mechanism for a hydraulic governor wherein variation in engine speed may be accomplished as a function of engine load without disturbing the operation of the delicately balanced pilot valve which forms a critical part of such governors.

Still another object of the present invention is to provide a speed-droop mechanism susceptible of convenient manual adjustment externally of the governor casing to any desired value of speed droop and characterized also by mechanical ruggedness and freedom from fragile parts.

Other objects and advantages of the present invention will appear as the specification proceeds.

I have illustrated certain typical embodiments of my invention in the accompanying drawing. In the drawing, Figure 1 is an external perspective view of a governor embodying my invention. Figs. 2 and 2' are sectional views, the section being taken along the line 2—2 of Fig. 1, the two fig-

ures showing alternative constructions. Fig. 3 is a fragmentary sectional view showing in greater detail a portion of the governor apparatus, the section being taken along the line 3—3 of Fig. 2'. Fig. 4 is a transverse sectional view bringing out in some detail a portion of the speed-droop apparatus, the section being taken along the line 4—4 of Fig. 2'. Fig. 5 is a fragmentary sectional view generally similar to Fig. 2' but showing a modified structure.

In the drawing A designates the casing structure of a hydraulic governor; B designates generally control mechanism for distributing pressure fluid for effecting changes in the fuel supply of the controlled engine in response to speed changes therein; and C designates generally the speed-droop mechanism—that is, the apparatus for effecting controlled variations in the speeder-spring tension as a function of the loading of the engine being governed. While I shall, for the sake of clarity, describe generally all the apparatus shown in the drawing, I shall in the present specification devote particular attention to the apparatus generally designated C, since the other novel features of the illustrated apparatus have been described at length and claimed in my said copending application, Serial No. 655,086, filed March 18, 1946, and now Patent No. 2,571,842, of which this is a division.

The casing A may be of any suitable construction. In the embodiment shown, it comprises a base plate 10, a frame structure 11 carried by said base plate, and a top dome 12 resting upon the body member 11. Dome member 12 is provided with a flange base 13 formed for registration with body member 11 and base 10. The adjoining surfaces of the three casing elements are provided with gaskets 15 to make them proof against oil leakage, and they are suitably bolted together by bolts 14.

The dome casing 12 is provided in its top portion with an annular shoulder 17 which serves as a support for the ball head 18 which carries fly weights 22. (As may be noted by comparison of the two figures, the reference numerals in Figs. 2' and 2 are similar for corresponding elements except that the reference numerals in Fig. 2 are given a prime designation. The structures shown in the two figures are functionally equivalent, representing alternative modifications of my speed-droop invention.)

The control mechanism B may be of any suitable type. In the form shown in Fig. 2', the fly weights 22 are pivoted on pins 23 to the ball head 18 and are provided with inwardly extend-

ing arms 24 having contact toes 25 turned downwardly. Toes 25 press upon the upper race of a ball thrust bearing 41, the lower race of which rests upon the upper flange 39 of the pilot-valve sleeve 40. Valve sleeve 40 is slidably and rotatably carried within a cylindrical bore 33 provided with suitably spaced inlet and outlet ports for the passage of pressure fluid into and out of pivot valve 40.

Concentrically carried within sleeve 40 is a shaft 27 which functions as the main governor drive shaft. Its outer end is equipped with a slot 28 suitable for connecting it to the output shaft of the engine to be governed, so that in operation shaft 27 rotates in synchronism with such output shaft. Near its lower end shaft 27 is provided with an integral gear member 29 which serves as part of the gear pump to be described hereinafter. Gear 29 rotates within a suitable pump chamber cut into base member 11. Above gear member 29 shaft 27 is provided with a reduced-diameter portion which passes through valve sleeve 40 with substantial clearance except at its uppermost end, where shaft 27 is machined to make a seal fit with sleeve 40. The reduced-diameter zone just described is broken up, however, by annular lands 31 and 32 which, in cooperation with sleeve 40, divide the interior of sleeve 40 into three chambers.

The upper end of shaft 27 passes through the center of thrust bearing 41 and is received within and keyed to ball head 18, so that rotation of shaft 27 accomplishes rotation of ball head 18 and of fly weights 22.

Gear 29 cooperates with gear 52 to form a gear pump carried within the pump chamber cut into the bottom surface of body member 11. Hydraulic fluid at sump pressure may be provided for the pump chamber by any suitable means. Rotation in the proper direction of the gears 29 and 52 will cause fluid pressure to build up in port 60 extending upward from the pump chamber, and such fluid will be carried into the transverse bore 61 shown in detail in Fig. 3. The maximum fluid pressure developed by the gear pump is under the control of the ball relief valve formed by valve seat 63, ball 62, and spring 64, carried in one end of the transverse bore 61. A gland 53, screwed into a threaded zone in the end of bore 61, serves as a stationary seat for spring 64. A passage 56 provides external communication to the low-pressure side of valve 62 and may be used to admit lubricating oil to the governor from the prime mover lubricating pump. A vertical bore 59 connects the low-pressure side of valve 62 to the inlet portion of the gear-pump chamber. It will be obvious to those familiar with gear pumps that when the pressure developed in bore 60 exceeds a critical value ball 62 will be moved off its seat and oil will be allowed to bypass into bore 59 and be re-circulated.

The high-pressure end of transverse bore 61 may be closed with a suitable threaded plug 57a. Since bore 61 and the elements of the gear pump are symmetrically arranged, the relative positions of gland 53 and plug 57a may be reversed if necessary, according to the direction of rotation of shaft 27. That is, if shaft 27 is in the direction which will produce high pressure in bore 59, then gland 53, ball 62, and spring 64 may be moved to the opposite end of transverse bore 61, being interchanged with plug 57a.

A bore 46 carries the pressure fluid from the gear pump to the pilot valve, such fluid being

introduced into the central pilot-valve chamber 51 by means of ports 44 and 45. Ports 47 cooperate with land 31 to provide control means for governing the flow of hydraulic fluid to and from a servomotor chamber 50 (Fig. 4) through passage 49, communicating with chamber 50. Exhaust ports 30 near the lower end of bore 33 provide an outlet to sump and thus maintain the zone below land 31 at sump pressure.

Supported within the chamber of the dome 12 between the fly weights 22 is a frusto-conical speeder spring 35. The lower end of the spring 35 rests upon an annular spring seat 36 having a cylindrical upward extension 42 which is slidably carried on bushing 43, pressed into the upper end of bore 33. (Two other annular bushings, denoted 43a and 43b respectively, are also pressed into bore 33 at spaced positions below bushing 43, as may be seen in Fig. 2'. The machined cylindrical interior surfaces of these bushings cooperate with the outer surface of valve sleeve 40.)

The pilot-valve sleeve 40 is preferably formed of thin metal, so that it will be light in weight and easily moved longitudinally of the shaft 27. It is suspended from upper spring seat 37 by means of its flange 39 resting on the shoulder 38, and which moves downwardly in response to pressure exerted upon the ball thrust bearing 41 by the toes 25 of the fly-weight arms 24. It will be seen, therefore, that the position of the pilot valve is determined by the balance position at which the centrifugal force developed by the fly weights and transmitted to the thrust bearing 41 balances the force exerted by the speeder spring 35.

In servomotor chamber 50 is a plunger 74, machined to fit snugly but slidably therewithin. Plunger 74 extends externally of the body member 11 at its outer end and is provided with a forked outer terminal 75 for connection to a control rod (not shown) connected to a fuel pump, mixing valve, steam throttle, or other device for controlling the supply of fuel or other energy medium to the prime mover. Plunger 74 is provided on its lower side with a keyway 76 in which a key 77 extends, the key being pressed in a hole provided therefor in body member 11, as shown in Fig. 4. Plunger 74 is also provided, above keyway 76, with a vertical slot in which a cam member 78 is mounted for pivotal movement upwardly and downwardly upon pivot pin 79. The upper surface of cam 78 bears upon the flat face of a flattened ball 80, which in turn supports a plunger 83 having its lower surface machined to conform to the spherical surface of ball 80.

The elevation of the cam member 78 is controlled by a threaded pin 81, having an inwardly extending point engaging cam 78 and an external slotted portion 82 adapted to be engaged by a screw driver for inward or outward adjustment.

The upper end of plunger 83 receives another flattened ball 84, the flat surface of which bears against the lower surface of block member 69 which, in turn, is pivoted to the casing by pin 10.

A fork member 66 has its bifurcated end portion extending around sleeve 42 and engaging the under surface of spring seat 36. The shank portion of fork 66 is provided with a boss 67 secured by pin 68 to block member 69. A leaf spring 34a bears at all times downwardly upon block 69 and thus exerts a continuous downward pressure on cam 78, through ball 84, plunger 83, and ball 80.

A rotatable cam member 71 is carried within

body member 11 immediately below fork 66, and is provided with a cylindrical shaft portion 72 journaled into body member 11 and extending externally, as shown in Fig. 1. The outer end of shaft 72 may be provided with a slot 73 to facilitate rotating it with a screw driver or other instrument. As may be seen from Fig. 2', fork 66 rests on cam 71 as a fulcrum, and the position of spring seat 36 (thus the compression of spring 35) may be varied by rotating shaft 72.

While the operation of the pilot-valve structure does not constitute a part of the present invention, I shall explain it briefly, for clarity, as follows: When the governed engine has been started, the speed at which it will stabilize will be determined by the compression of speeder spring 35, and thus by the manually determined position of shaft 72. Initially, sleeve 40 will be raised by spring 35 and pressure fluid will accordingly be admitted through port 47 and bore 49 into servo chamber 50. This will result in outward movement of plunger 74 and consequent increase in the supply of fuel or other energy-bearing material to the governed engine. As the engine's speed increases responsively to this supply of additional fuel, fly weights 22 will cause increasing pressure on bearing 41, resulting in downward movement of sleeve 40 until a position of stabilization is reached at which the port 47 is in registration with land 31. The engine will then run at the stabilized speed until some event, such as a change in load, occurs to make it speed up or slow down. If it should speed up, sleeve 40 will be pressed downwardly beyond its equilibrium position and some of the pressure fluid contained within servo chamber 50 will be allowed to escape via bore 49 and sump ports 30. This will result in an inward movement of plunger 74 and consequent reduction in the fuel supply to the governed engine. (Plunger 74 is externally spring loaded (not shown) so that the spring tends to move the servo plunger inwardly to "fuel-off" position.)

Should the change in load cause the engine speed to decrease, the force of spring 35 will cause the sleeve 40 to rise, thus admitting additional pressure fluid to bore 49 from chamber 51, causing the servo plunger 74 to move further outward and thus increase further the engine fuel supply.

The present invention relates particularly to the means herein provided for producing "speed droop," that is, for causing the speed of the engine to go down to a desired degree as the load on it increases. That result is accomplished in the Fig. 2' form of the invention by the apparatus, just described, involving the plunger 83 and the cam 78. When, as a result of increasing load, the plunger 74 moves outward, cam 78 causes plunger 83 to rise, and the position, therefore, of pivot pin 68 is also caused to move upward. As a result, fork member 66, turning on cam 71 as a fulcrum, permits spring seat 36 to move downward, with a resulting reduction in the compression of spring 35. This movement causes the engine to stabilize at a speed somewhat lower than it formerly had. The quantity of speed reduction for a given change in load is within the control of the operator by means of adjustment of pin 81.

As I have heretofore mentioned, Fig. 2 shows apparatus generally similar to Fig. 1 except that I have therein shown a modified form of my speed-droop apparatus. In that structure, I have provided, as a manual speed-control device, a

shaft 72', journaled in the casing member 11' for external manual rotation, as with shaft 72 in the Fig. 2' embodiment. On its inner end, shaft 72 has a flattened surface carrying cam 91, bearing upon a bent bifurcated arm 89 which presses on the underside of spring seat 36'. The opposite end of arm 89 is secured to a ball-like member 84' the spherical surface of which is received within a suitably formed seat in the upper end of plunger 83'. Plunger 83' is actuated by cam 78' in the same manner heretofore described with respect to plunger 83 in the Fig. 2 embodiment. Manual speed control in the Fig. 2 form of the invention is accomplished by rotation of shaft 72, which raises or lowers arm 89 and thus raises or lowers spring seat 36'. The position of spring seat 36' and the compression of speeder spring 35 are modified by changes in the position of plunger 74' by the raising or lowering of member 84' by way of plunger 83' and flattened ball 80'.

Fig. 5 shows a slight modification of the Fig. 2 structure in which upper ball member 84' is dispensed with and the plunger 83' is replaced by a plunger 83a having its upper end modified to provide a pivot pin 68', on which the inner end of arm 89 is pivoted. The operation of the Fig. 5 structure is similar to that of the Fig. 2 structure except that the pivoting action around pin 68' is substituted for the rotation within its seat of ball member 84' as the plunger is raised and lowered.

While I have in the present specification described in considerable detail certain specific embodiments of my invention, it is to be understood that those are illustrative only, and that the scope of my invention is not limited thereto but is to be determined primarily with reference to the appended claims.

I claim:

1. In governor mechanism of the type wherein the movement of a fluid servo-motor adjusts the speed of a prime mover and a control mechanism for moving said servo-motor is responsive to the loading of a speeder spring in the control operation, apparatus for automatically changing the loading of the speeder spring during movement of the servo-motor, comprising a seat for said speeder spring, an elongated speed load control member engaging at one end said speeder spring and being pivotally connected at its other end to a pivotally-mounted supporting block, a fulcrum for said control member intermediate the ends thereof, a cam carried by said servo-motor, and cam follower means for transferring the force movement of said cam to change the position of the pivotal connection of said control member and said block to change the loading of said speeder spring.

2. The structure of claim 1 in which said fulcrum is a cam adjustably mounted to provide a loading control for said speeder spring independent of the cam loading of said spring.

3. In speed governor mechanism of the type wherein the movement of a fluid servo-motor adjusts the speed of a prime mover and a control mechanism for moving said servo-motor is responsive to the loading of a speeder spring in the control operation, apparatus for automatically changing the loading of the speeder spring during movement of the servo-motor, comprising a seat for said speeder spring, an elongated lever engaging at one end said speeder spring and being pivotally connected at its other end to a pivotally-mounted supporting block, an ad-

justable cam intermediate the ends of said lever and providing a fulcrum therefor, a cam carried by the piston of said servo-motor and adapted to move therewith, a slidably-mounted plug extending between the pivotally-connected end of said lever and said second-mentioned cam and adapted to change the position of the pivotal connection of said lever and said block to change the loading of said speeder spring, and means for urging the pivotally-connected end of said lever and said block into engagement with said second-mentioned cam.

4. The structure of claim 3 wherein the cam carried by the piston of said servo-motor is adjustably carried thereby, and a manually-adjustable pin carried by the piston of said servo-motor is adapted to adjust the cam.

5. In a hydraulic speed-control governor for engines, a servo piston adapted upon movement to vary the speed setting of the engine, a speeder spring adapted upon changes of the loading thereof to actuate said servo piston, means arranged with said servo piston and said speeder spring to move said servo piston in response to changes in the loading of said spring, a seat for said speeder spring, a lever engaging at one end said spring seat and being pivotally connected at its other end to a pivotally-mounted supporting block, means for changing the speed setting of said governor comprising a rotatably-mounted cam providing a fulcrum for said lever intermediate the ends thereof whereby movement of said cam changes the loading of said speeder spring, and speed droop apparatus including a servo cam adjustably carried by the piston of said servo-motor, a cam follower extending between said servo cam and the pivotally-connected end of said lever and adapted upon movement of said cam to change the position of the pivotally-connected end of said lever to vary the loading of said speeder spring, and spring means for biasing said cam follower against said servo cam and the pivotally-connected end of said lever against said cam follower.

6. The structure of claim 5 wherein said cam follower comprises a slidably-mounted plunger having at each end a ball seat, and a ball in each of said seats engaging said lever and said servo cam, the ball engaging said servo cam having a flattened surface portion adapted to ride upon the cam surface of the servo cam.

7. In control apparatus, a control member, an axially movable member responsive to conditions imposed thereon by the control member and being movable in response to such conditions to control mechanism arranged therewith, a cam carried by said axially movable member, a lever

coupled to said control member and being adjustably positionable to change the state of said control member and thereby change conditions imposed by said control member upon said movable member, and a cam follower in engagement with said cam and being coupled to said lever for adjusting said lever in accordance with the position of said cam, said cam follower comprising a plunger having at least at one end thereof a ball seat and at its other end being coupled to said lever in an arrangement whereby movement of said plunger changes the position of the lever, and a ball in said seat and in engagement with said cam.

8. The structure of claim 7 wherein said plunger is equipped at each end with a ball seat, and a ball is mounted in the second seat and is in engagement with said lever.

9. The structure of claim 8 wherein at least one of said balls is provided with a flattened engaging surface.

10. The structure of claim 7 wherein said plunger at the end thereof coupled to said lever is pivotally connected thereto.

11. In governor apparatus, a speeder spring, a servo piston in operative arrangement with said speeder spring and movable in response to condition changes imposed thereby, and speed droop apparatus comprising a lever engaging said speeder spring and being adjustably mounted adjacent one end thereof, a cam carried by said servo piston, a plunger mounted between said cam and lever for movement therebetween and having at each end a ball seat, and a ball in each of said seats, one of said balls being in engagement with said lever and the other of said balls being in engagement with said cam.

12. The structure of claim 11 in which said lever engages at an end thereof said speeder spring.

13. The structure of claim 11 in which said lever engages said speeder spring intermediate the ends of the spring, and an adjustable cam in operative arrangement with said lever at the end thereof most remote from the adjustably mounted end provides manual adjustment of the tension in said speeder spring.
